UNITED STATES PATENT OFFICE

99,109

DESIGN FOR A FLOOR BRUSH

Frederic J. Bickel, Cleveland, Ohio, assignor to
The Osborn Manufacturing Company, Cleve-
land, Ohio, a corporation of Ohio

Application February 11, 1936, Serial No. 61,093

Term of patent 14 years

To all whom it may concern:

Be it known that I, Frederic J. Bickel, a citizen of the United States, and a resident of Cleveland, county of Cuyahoga, and State of Ohio, have invented a new, original, and ornamental Design for a Floor Brush, of which the following is a specification, reference being had to the accompanying drawing, forming a part thereof.

In the accompanying drawing:

Fig. 1 is a perspective view of a floor brush, showing my new design;

Fig. 2 is a side elevation;

Fig. 3 is a plan view; and

Fig. 4 is a transverse section of the back (omitting bristles), on the plane 4—4, Fig. 3.

The back of the brush when seen in side view is characterized by a long sweeping curved de-

scent in each direction away from the middle, and flattening towards either end. The ends and the upper edges are rounded, so that the surfaces of top, sides, and ends of the brush back are joined by graceful curved surfaces.

The back is further characterized by having a slightly elevated broad central stripe running its entire length and going down over the ends.

The stripe is of a color or shade contrasting with the remainder of the back. The shading in the drawing indicates shape and color contrasts and is not intended to indicate any particular color.

What I claim is:

The ornamental design for a floor brush substantially as shown and described.

FREDERIC J. BICKEL.
